DISPENSING CONTAINER FOR LIQUID POLISH

Lucien Rias, Lyon, France, assignor to Gonnet S.A.
Villeurbanne, Rhone, France, a corporation of France

Filed July 15, 1968, Ser. No. 12,771

Term of patent 3½ years

Int. Cl. D9—01

U.S. Cl. D9—10

FIG. 2

FIG. 3

FIG. 4

FIG. 5

I claim:

The ornamental design for a dispensing container for liquid polish, substantially as shown.
